UNITED STATES PATENT OFFICE.

ROBERT H. MUELLER, OF DECATUR, ILLINOIS, ASSIGNOR TO ADOLPH MUELLER,
TRUSTEE, OF DECATUR, ILLINOIS.

SERVICE-BOX.

1,394,754.

Specification of Letters Patent. Patented Oct. 25, 1921.

Application filed May 11, 1917. Serial No. 167,950.

To all whom it may concern:

Be it known that I, ROBERT H. MUELLER, a citizen of the United States, residing at Decatur, in the county of Macon and State 5 of Illinois, have invented new and useful Improvements in Service-Boxes, of which the following is a specification.

The present invention relates to service boxes which are ordinarily used in connection with stop cocks which control the flow of fluids, as water and gas, from the mains to the house service pipes, such service boxes permitting ready access of a stop cock key to the cocks for the purpose of opening or closing them. These stop cocks are at various depths in different localities, and it has been heretofore proposed to make a telescoping service box which could be lengthened to suit the different depths 15 within a wide range, and do away with the necessity of making service boxes in different lengths to take care of each particular locality.

The present invention has to do with telescoping service boxes of this type, and has for its object to provide a simple and economical construction, and one which may be adjusted to various heights, and which when once placed in position and adjusted 25 will maintain its position of adjustment during the filling of a trench, and without the necessity of its being held or propped up while the filling is being done.

In order that the invention may be clear 30 to those skilled in the art I have shown in the accompanying drawings embodiments of my invention, and in said drawings:

Figure 1 is a sectional view of a service box embodying my improvements.

Fig. 2 is a top view of the service box shown in Fig. 1, with the cover removed.

Fig. 3 is a view partly in section on the line 3-3 of Fig. 2.

Fig. 4 is a sectional view of a service box 45 of a slightly modified construction from that shown in the preceding views.

Fig. 5 is a transverse sectional view on the line 5-5 of Fig. 4.

Fig. 6 is a view showing a slightly modified construction.

Fig. 7 is a vertical sectional view of the form of the invention shown in Fig. 6.

Referring to the drawings by numbers, like

numbers indicating like parts in the several views, 10 indicates the stop cock housing 55 having an internal chamber of sufficient size to receive the stop cock, and the said member 10 may be split or arched if desired, as shown at 11, so as to straddle the stop cock and pipe. The upper part of the said member 10 comprises the tubular section 12 of reduced diameter, and suitably secured to the section 10, or it may, if desired, be formed integral therewith. At its upper end, the section 12 is provided with a head 13, in 60 the socket of which head the upper end of the section 12 is seated, the head being chamfered so as to form a seat to receive the upper end of the section 12 and give a smooth uninterrupted bore through the section 12 65 and head 13. A convenient method of locking the head 13 and section 12 together is shown in Figs. 1 and 2, in which it will be observed that the head 13 is cut diametrically, as at 14, and the wall of the section 12 70 is swaged outwardly, as at 15, into the cut 14 so as to firmly lock the parts together. This method of locking the parts together is a very desirable one for the reason that it may be readily accomplished with a minimum of labor and after the parts are brought to assembled condition. The reduced section 12 having telescoped with the upper section 16, the head 13 will be dropped over the upper end of the section 12 and the locking lugs 75 15 swaged outwardly in the diametrical slots 14 so as to lock the section 12 and head 13 securely together. It will be seen that since the head 13 is in non-rotatable relation to the upper section 16, that such method of locking 80 the parts together is a very desirable and convenient one, since it avoids the necessity of any rotating interlocking movement between the head and the lower section and effectively locks the parts against separation 85 90 longitudinally or rotatably with respect to each other. That construction shown in Fig. 1 in which the housing 10 is cast, while the telescoping section 12 is formed of standard piping and suitably secured to the housing 100 and the locking head 13, which head is also cast, is a convenient and advantageous construction in that by combining the cast housing and the pipe section and the head, as shown, production and assembling are very 105 quickly done and at a minimum cost, the

housing and head being cast and the telescoping section being cut in appropriate lengths from standard drawn piping.

The head 13 is provided on its exterior 5 with a lug or lugs 15', which, as will presently appear, serve as engaging means in connection with the upper service box member, presently to be described, and prevent relative rotation of the lower and upper box 10 members, while permitting free longitudinal movement of the members.

The upper box member comprises the tubular section 16 having at its lower end an apertured head 17, in the wall of which is 15 formed an annular groove 18, in which is seated a contractile spring 19 of non-corrodible metal, the exterior diameter of which is less than the diameter of the groove 18, so that when the spring 19 is snapped in place, 20 while it will be held against accidental displacement, there will be ample room for its expansion and contraction. The reduced section 12 of the lower casing member engages the aperture in the head 17 of the upper member 16 with a close sliding fit, the spring 19 being of such internal diameter as 25 that it will grip the section 12 with sufficient friction to maintain the upper and lower sections in any position of adjustment to which 30 they may be brought.

The upper section 16 is provided with a groove or grooves 20, in which the lugs 15' of the lower member engage and slide freely, these lugs and grooves preventing any relative rotation of the parts, so that the cover plate 21 with which the upper section is provided may be screwed or unscrewed without rotating the other parts when the box is in position, and the cap plug 22, which is ordinarily removed when access to the stop cock 40 by means of the stop cock key is desired, may be removed or replaced without danger of disturbing the relative position of the box members.

45 It will be observed that with the construction shown the reduced section 12 of the lower member and the upper member 16 of the box are adjustable relative to each other by straight right line movement and rotary 50 movement of the parts relative to each other for right line adjustment is done away with. Furthermore, the friction connection between the reduced section 12 of the lower member and the upper member 16 is such 55 that after a service box has been set, and the filling in is taking place, danger of dirt getting between the sliding joint between the members and entering the chamber is eliminated, not only by reason of the friction 60 ring, but also by reason of the fact that the joint is formed at the lower end of the upper section, and the lower member telescopes within the upper member instead of telescoping the upper member within the lower 65 member; as has in some instances been the

practice heretofore. Furthermore when the fill is completed the dirt packs solidly about the box and beneath the lower end of the upper member, so that it is effectually held against any shifting due to pressure of traffic 70 on the top.

In the form disclosed in Figs. 4 and 5 the construction is somewhat simplified, for in that form I have dispensed with the interlocking head. This form comprises the 75 enlarged cock receiving chamber 23, having, as shown, a reduced section 24 integrally formed therewith, which telescopes in the plain pipe section 25, which pipe section has at its lower end the head 26 to receive the contractile friction spring 27, which is mounted in the groove 28 in the head 26, provision being made for proper expansion of the spring by making the groove 28 of greater 80 diameter than the normal diameter of the spring. The section 25 is provided at its upper end with any suitable cover, as 29.

The construction shown has the advantages set forth in connection with the forms heretofore described, and the further advantage that it may be very cheaply constructed.

In the form of the invention shown in Fig. 1 provision is made for preventing rotation of the upper and lower sections relative to each other, while in that type disclosed in Fig. 4 no such provision is made. Relative rotation of the parts may, of course, be prevented by means other than those heretofore described, and one convenient manner of attaining this is shown in Fig. 6, which is a plan view, with the top cover removed, of a service box. In this form of the invention the upper member 30 will be elliptical in cross section, and the upper part 31 of the lower member will be shaped to conform to the elliptical bore of the upper member 30 by swaging out the upper end of the lower member, or by securing thereto, if desired, 100 an independent elliptically shaped head. 110 With this construction it will be obvious that while the elliptical parts are free to move longitudinally, there can be no rotation of the parts relative to each other, because of this elliptical formation. It is obvious that 115 the bore of the upper member 30 and the head 31 of the lower member might be formed in shapes other than elliptical in cross section, and secure this same locking action.

Such variations from the embodiments here disclosed as are within the range of mechanical skill I deem to be within the spirit of my invention, and do not, therefore, limit myself to the details disclosed, 125 except in so far as I am limited by the terms of the appended claims.

I claim:

1. The combination, in a service box, of a lower member having an enlarged housing 130

at its lower end and a reduced section extending therefrom, an upper member of larger diameter than said reduced section, which upper member has an unobstructed interior to permit free longitudinal adjustment of that member relative to said reduced section, an annularly grooved head at the lower end of said upper section closely embracing said reduced section to make a snug joint therewith, a friction ring seated in the annular groove of said head to grip said reduced section and maintain the parts in adjusted position, and a head carried at the upper end of said reduced section and interlocked with said upper section against rotation but free to move longitudinally therein.

2. The combination, in a service box, of a lower member having an enlarged cast housing at its lower end, a separate drawn pipe section of reduced diameter secured thereto and extending upwardly therefrom, an upper member of larger diameter than said re-

duced section having longitudinally disposed ribs on its interior telescoping over said reduced section, an annularly grooved head at the lower end of said upper section closely embracing said reduced section to make a snug joint therewith, a friction ring seated in the groove of said head to grip said reduced section and maintain the parts in adjusted position, and a cast head interlocked with the upper end of said reduced section by outwardly swaged lugs engaged with the ribs on the interior of said upper section to lock the parts against rotation but leaving them free for longitudinal movement.

In testimony whereof I have hereunto set my hand in presence of two subscribing witnesses.

ROBERT H. MUELLER.
